UNITED STATES PATENT OFFICE.

WILLIAM D. WRIGHT, OF CONCORD, MASSACHUSETTS.

VANITY CASE.

Application filed June 29, 1923. Serial No. 648,475.

To all whom it may concern:

Be it known that I, WILLIAM D. WRIGHT, a citizen of the United States, and resident of Concord, in the county of Middlesex, 5 State of Massachusetts, have invented certain new and useful Improvements in Vanity Cases, of which the following is a specification.

The main object of the invention is to 10 provide a vanity case fitted with two mirrors, one a plain flat reflecting mirror and the other one a magnifying mirror. The purpose of providing a vanity case with two types of mirrors is to permit the user to 15 examine a normal size reflection in order to note the normal and ordinary appearance of the skin and then to examine a magnified reflection in order to more clearly note the skin condition.

20 A further object of the invention is to provide means whereby the user of a skin lotion or cream may very accurately note the progressive betterment of the condition of the skin, the magnifying mirror enabling 25 the user to note accurately the condition of the skin, while the ordinary and normal appearance of the skin will be reflected by the plain flat mirror.

In the drawings, Fig. 1 is a perspective 30 view of the vanity case open;

Fig. 2 a transverse sectional view of the case closed;

Fig. 3 a transverse sectional view of the case closed taken on the line 3—3 of Fig. 2; 35 Fig. 4 a transverse sectional view similar to Fig. 3 showing the case open; and

Fig. 5 a view of the hinge connecting the two sections of the case, the case being shown as open and broken away.

40 Referring to the various parts by numerals, 1 and 2 designate two frames which constitute two box sections. Each frame is formed with a body part 3 and a continuous side flange 4 which extends entirely around 45 the body part so that each flanged frame forms substantially one half of a box. When the side flanges of the two frames are brought together, as shown in Figs. 2 and 3, a closed dust proof box is formed adapt- 50 ed to contain a powder puff and like arti-

cles. The two frames or box sections are connected together by a hinge 5 secured to the flanges 4. This hinge is preferably a spring snap-hinge of any suitable form designed to hold the two box sections closed 55 or to hold them open at right angles to each other. As shown in the drawing the hinge is provided with a bowed spring 6 having its ends engaged over flanges 7 formed on the box sections. The tension of the 60 spring 6 forces the flanges 7 toward each other so that when the box is closed, as shown in Fig. 3, the tension of the spring holds it closed; when however, the box is open, as shown in Fig. 4, the tension of the 65 spring tends to hold it open. Of course, it will be understood that any suitable form of spring hinge may be used.

In the frame 1 is secured an ordinary flat reflecting mirror 8, said mirror being 70 secured in position by a retaining ring 9. The flange 4 of the section 1 is considerably higher or wider than the thickness of the mirror. Within the frame 2 is secured a magnifying mirror 10, said mirror being 75 convex on its inner side, that is to say, the side next to the body part 3 is convex. The exposed side of the magnifying mirror is preferably flat as shown in the drawings. The mirror 10 is secured in position by 80 means of a retaining ring 11. The mirror 10 is of less thickness than the width of the flange 4 of the section 2 so that when the two sections are closed or brought together to form a closed box there will be 85 a space between the exposed faces of the mirrors, said space constituting a receptacle in which a powder puff and other articles may be contained.

The hinge is preferably formed with stops 90 12 which limit the outward swinging of the two box sections so that the spring will maintain them at right angles to each other when in open position.

What I claim is:

1. A vanity case or box comprising two box sections adapted to fit together and form a completely closed box, a spring snap-hinge connecting said box sections and adapted to hold the box sections either closed 100

or open at right angles to each other, a plain flat mirror in one box section, and a magnifying mirror in the other box section.

2. A vanity case or box comprising two frames formed with side flanges extending entirely around the frames, a spring snap-hinge connecting said frames and adapted to hold them together with their side flanges in contact or separated and at right angles

to each other, a plain mirror in one frame, 10 and a magnifying mirror in the other frame, said mirrors being enclosed by the said side flanges and of less thickness than the width of the said flanges.

In testimony whereof I hereunto affix my 15 signature.

W. D. WRIGHT.
